INVENTOR.

George L. Grow

BY *Acme* (illegible)
ATTORNEYS.

UNITED STATES PATENT OFFICE.

GEORGE L. GROW, OF COVINGTON, KENTUCKY.

ADVERTISING PROJECTOR.

Application filed August 10, 1923. Serial No. 656,726.

To all whom it may concern:

Be it known that I, GEORGE L. GROW, a citizen of the United States, and a resident of Covington, in the county of Kenton and 5 State of Kentucky, have invented certain new and useful Improvements in Advertising Projectors, of which the following is a full, clear, and exact description, reference being had to the accompanying drawings, 10 forming part of this specification.

My invention relates to machines such as are employed for projecting on a screen advertising matter from photographic plates in which a number of different illustrations 15 are presented in series, each exposed for a limited time and then automatically changed for the succeeding plates.

The object of the invention is to provide a convenient and effective apparatus for 20 mounting the photographic slides and for bringing each slide automatically between the light and the projecting lens, and exposing same for a limited time.

The invention consists of that certain 25 novel construction and arrangement of parts to be hereinafter particularly pointed out and claimed, whereby the above results are attained.

In the drawings:

Figure 1 is a perspective view of the apparatus with the enclosing casing removed.

Figure 2 is a vertical section taken through the plate reels with parts in front elevation.

Figure 3 is a detail section taken in the line 3—3 of Figure 2.

Figure 4 is a perspective view of one of the slide holders.

The apparatus is mounted in a substantial frame 1, preferably U-bars of the necessary side and cross pieces upon which is mounted the projecting lens 2, and the casing 3 enclosing the light, no special description of which need be given, as these parts 40 form no part of the present invention, which as stated relates to the slide holder and its operating mechanism.

Suitably journaled in standards 3, 3, on the main frame, is a shaft 4 which carries 50 a spool 5 square in cross section, enclosed in guide disks 6, 6, at each end. On the outside of the journal bearing for the shaft 4 is secured a hub 7, carrying four arms or spokes 8, 8, 90 degrees apart. These spokes 55 are engaged intermittently by an arm 9 terminating in a bent over or hooked portion

10 to properly engage the spokes. The arm 9 is secured to a shaft 11 journaled in the frame and carrying a gear 12 which in turn engages a worm 13 on shaft 14 driven by a suitable electric motor 15 or other source of power. The speed of the motor or other driving power will determine the speed of the intermittent rotation of the square spool 5, as will be readily understood.

The construction of the slide holders which carry the slides and which are connected in series to form an endless chain constitutes one of the important features of my invention.

One of these holders is illustrated in Figure 4. It comprises a sheet metal frame of base 16 and sides 17, 17, with the upper ends turned over to form tongues 18, 18. Ears 19 are turned up out of the metal for the base and sides which form retaining clips for the slide. To insert the slide in the holder, all that it is necessary to do is to spring out the sides 17 slightly to permit the slide to pass the tongues and seat it in the guide clips 19, and releasing the sides the tongues cover the open edge of the slide and hold it firmly in place. An endless chain is made up of these slide holders by securing them side by side with rings or loops 20.

As many of these slide holders are employed as there may be advertisements for display, and the chain may be lengthened or shortened by the addition or removal of the holders.

The chain open is hung over the square spool 5 and then the free ends are hooked together to form an endless chain. The width of the square faces of the spool 5 is just sufficient to hold the base of one slide holder and the loops 20 are sufficiently loose to permit the adjacent holders to occupy a right angled position to the intermediate holder. To more effectively permit this positioning, the edges of the square spool are 95 grooved at 21 to receive the loops 20.

To hold the square spool in position after each quarter turn, I provide a spring pressure bar 22 (Figure 3), one end of which is secured to the standard 3, and the other end 23 slightly curved, bears on top of the spool 5, so that the spool is held securely in proper position.

In order to maintain the endless chain of holder from swinging loose, I run the chain 110 at the lower end over a guide roller 24, which is mounted on a shaft 25, the ends

of which are journaled in slotted bars 26, 26 depending from the main frame. An adjustable spring plate 27 on each side secured by a screw 28 in its respective slot 29 of the bar 26 exerts the proper tension on the guide roller 24 to maintain the tautness desired.

The operation of the apparatus will be obvious. Slide holders are made up of 10 the number of slides to be projected, and each slide is readily and easily mounted in the holder. The motor is started and depending on its speed, which is greatly reduced by the worm and gear construction, 15 the square spool will be rotated a quarter turn each time the arm 9 contacts with one of the spokes 8 to bring the next succeeding slide in front of the projecting lens where the slide will remain until the gear 12 has 20 made rotation to bring the arm 8 back to its former position, and into contact with the next spoke.

By reason of the pressure of the spring 25 plate 22 as soon as the edge of the square block passes the vertical position, the spring pressure will snap the block into its next position, thus bringing the next slide into projecting position.

Having thus described my invention, what 30 I claim as new, and desire to secure by Letters Patent, is:—

1. In an apparatus of the character specified, means for carrying and intermittently presenting photographic slides to a projecting device, comprising a series of sheet metal slide holders, and loops loosely connecting them together side by side in an endless chain, a rotatable block, square in cross section over which said chain is suspended, and a floating roller under spring tension around which the endless chain is drawn, arms projecting at right angles from the block, with a power operated shaft, car-

rying an arm to contact with said block arms in turn to shift the same intermittently a 45 quarter of a revolution.

2. In an apparatus of the character specified, a series of sheet metal slide holders, each formed from an integral resilient strip of sheet metal folded to form an open rectangular holder, with tongues bent inwardly to form the top and with lugs bent up from the strip to hold the slides with the sides of the holder adapted to be sprung out to receive the slides, and loops to connect the slide holders into an endless chain, and means for moving the chain to present one slide holder at a time to the projecting lens.

3. In an apparatus of the character specified, a series of resilient sheet metal slide holders, each formed from an integral strip of sheet metal folded to form a holding frame adapted to be sprung out to receive the slides, with loops to connect the holders into an endless chain, said chain supported on a horizontal rotatable support for driving same, with an idler roller at the bottom of the chain, with spring bearing on said roller to maintain tension on the endless chain, as it is shifted.

4. In an apparatus of the character specified, a series of sheet metal slide holders, each formed from an integral strip of sheet metal folded to form a holding frame, with loops to connect the holders into an endless chain, said chain supported on a horizontal rotatable support for driving same, with an idler roller at the bottom of the chain, slotted depending bars in which said roller is adjustably mounted, with adjustable springs secured to said bars, bearing upon the roller spindle to maintain and adjust the tension on the endless chain.

GEORGE L. GROW.
